UNITED STATES PATENT OFFICE.

EDWARD MOWRY, OF ROCK FALLS, ILLINOIS, ASSIGNOR TO INTERNATIONAL HARVESTER COMPANY, A CORPORATION OF NEW JERSEY.

WINDROW LOADER.

Application filed January 7, 1921. Serial No. 435,603.

To all whom it may concern:

Be it known that I, EDWARD MOWRY, a citizen of the United States, residing at Rock Falls, in the county of Whiteside and 5 State of Illinois, have invented certain new and useful Improvements in Windrow Loaders, of which the following is a full, clear, and exact specification.

My invention relates to hayloaders and 10 more particularly to the endless elevator type.

The principal object of my invention is to provide an improved pivoted section positioned at the delivery end of the elevator 15 of a hayloader and adjustable with respect thereto.

A further object is to provide an improved adjustable mechanism for the pivoted section of the elevator within easy 20 reach of the operator on the hay rack.

These and other objects are obtained by providing a pivoted section to the elevator frame, the upper end of said section being adapted to support a crank shaft for winding 25 a flexible element for effecting the adjustment of the pivoted section.

In the accompanying drawings, which illustrate the preferred embodiment of my invention—

30 Figure 1 is a side elevational view of a standard endless belt hayloader embodying my invention.

Figure 2 is a top plan view of the pivoted section.

35 Figure 3 is an enlarged detail view, partly in section showing the pivoted connection.

Figure 4 is an enlarged detail sectional view of the ratchet mechanism for locking 40 the pivoted section in adjusted positions.

The same reference character designates like parts throughout the several views.

The hayloader here shown is of the standard endless belt type and comprises the 45 usual forwardly extending side frame members 5, disposed on the opposite sides of the machine having their forward ends mounted on the front carrying wheels 6 and their rear ends mounted on rear traction wheels 7 which carry the elevator 50 wheel 8.

The elevator frame comprises upwardly and forwardly inclined members 9 and 10 disposed upon the opposite sides of the 55 machine and having their upper ends support-

ed by means of vertically disposed frame members 11, fixed to side frame members 5. The frame member 10 is supported by the transversely disposed frame angle 12 fixed to the vertical member 11.

60 The mechanism for elevating the hay includes a pair of chains or endless belts 13 disposed on the opposite sides of the machine and having cross slats 14 spaced at intervals attached to said belts. These 65 belts 13 engage the wheels 8 and are operatively driven thereby to elevate the hay.

Pivotedly attached to the frame member 10 at 15 is an adjustable section 16. This 70 adjustable section comprises the side members 16' disposed on the opposite sides of the machine and having diagonally disposed cross braces 17 fixed thereto and also an additional reinforcement is provided by a cross bar 18 secured to the sides 16' at the 75 upper end of the extension. Securely fixed adjacent the upper ends and to the outsides of the members 16' are a set of brackets 19 which are adapted to adjustably receive the bearing members 20 of the shaft 21. 80 Formed integrally with the shaft 21 is a crank handle 22 for the purposes herein-after set forth. Journaled on the shaft 21 are the flanged pulleys 23 over which the 85 endless belt 13 passes. The mechanism for adjusting the pivoted section includes extensions of the shaft 21 forming winding drums 24 outside the pulleys 23. Securely fixed to these drums 24 are flexible members or wires 25, which are adapted to be 90 wound around the drums 24. Connected to and extending rearwardly from the flexible member 25 is a connecting rod 26 which is pivotally connected to the upper end of the vertically disposed frame member 11. The 95 side members 16' have securely fixed adjacent their lower ends hinge members 27 provided with an arcuate slot 28 adapted to guide and limit the adjustable section by means of a pin 29 extending thru the slot 28 and fixed to the frame member 10. The 100 adjustable section 16 is hinged at 15 to brackets 30 disposed on the opposite sides of the loader and fixed to the transversely disposed angle 12 by means of a bolt 31, 105 as shown in Fig. 3.

From the above description it will be noted that in order to effect an adjustment of the pivoted elevator section, the hand lever is actuated in a manner to wind or un- 11

wind the flexible member 25 upon the drums 24 and that means are also provided for locking the extension in the desired position of adjustment comprising a ratchet member 32 fixed to the shaft 21 and adapted to engage a gravity pawl 33, as shown in Fig. 4. The gravity pawl 33 is normally held in engagement with the ratchet 32 by a weight 34 formed integrally with the pawl. The 10 pawl 33 is pivoted at 35 to a bracket member 36 having a bifurcated portion 37 adapted to engage both sides of the ratchet 32 and journaled on the shaft 21. The end of the bracket 36 has a rearwardly extending 15 portion 38 adapted to protrude through an aperture 39 in the cross bar 18 in a manner to permit a sliding movement relative thereto.

From the above description it will be 20 noted that a tightening of the endless elevator belt 13 may be had by adjusting the bracket bearings 20 and thereby adjusting the shaft 21 relative the frame members 16' and permitting the extension 38 of the 25 bracket 36 to slide relative to the cross bar 18.

In order to prevent the slats 14 from being caught on the ratchet member 32, a 30 wheel 40 over which the slats ride is journaled on the shaft 21 and held from lateral displacement on one side by a collar 41 fixed to the shaft 21 and on to the other side by the bracket 36.

From the above description it will be 35 noted that I have provided a very simple, durable and efficient adjustable pivoted section to the elevator of a hayloader and one in which the adjustments of same may be readily made by the operator on the hay 40 rack.

Having described one embodiment which my invention may assume, it is to be understood that the same may be modified without departing from the spirit and scope of 45 the appended claims.

What I claim as my invention and desire to secure by Letters Patent is:

1. In a hayloader, a frame, carrying 50 wheels therefor, an elevator frame carried by said first mentioned frame, an elevator section pivoted to said elevator frame, and means including a crank, and a shaft extending across the delivery end of said section for adjusting said section in a plurality of positions.

2. In a hayloader, a frame, carrying wheels therefor, an elevator frame carried by said first mentioned frame, an endless belt mounted on said elevator frame and operatively driven by said wheels, an elevator 60 section pivoted to said elevator frame comprising a shaft positioned at the delivery end of said section and forming bearings for pulleys over which said endless belt is operatively driven and means forming a part 65 of said shaft for adjusting said section.

3. In a hayloader, a frame, carrying wheels therefor, an elevator frame carried by said first mentioned frame, an endless belt mounted on said elevator frame and operatively driven by said wheels, an elevator 70 section pivoted to said elevator frame comprising a shaft positioned at the delivery end of said section and forming bearings for pulleys over which said endless belt is 75 operatively driven, and means for rotating said shaft for adjusting said section.

4. In a hayloader, a frame, carrying wheels therefor, an elevator frame carried by said first mentioned frame, an endless 80 belt mounted on said elevator frame and operatively driven by said wheels, an elevator section pivoted to said elevator frame comprising a shaft positioned at the delivery end of said section and forming bearings for pulleys over which said endless belt is operatively driven, a crank for rotating 85 said shaft for adjusting said section and means journaled on said shaft for locking said shaft in predetermined positions of adjustment.

5. In a hayloader, a frame, carrying wheels therefor, an elevator frame carried by said first mentioned frame, an elevator section pivoted to said elevator frame and means including a shaft movable laterally 90 with respect to said section and rotatably adjustable for adjusting said section in a plurality of positions.

6. In a hayloader, a frame, carrying 100 wheels therefor, an elevator frame carried by said first mentioned frame, an elevator section pivoted to said elevator frame, means including a shaft mounted in said section for lateral and rotary adjustment, and 105 means carried by said shaft for locking shaft against rotary movement.

In testimony whereof I affix my signature.

EDWARD MOWRY
